LEWIS F. MOORE, OF ROANOKE, AND PRESTON CRAIGHILL, OF LYNCHBURG, VIRGINIA, ASSIGNORS TO WALKER MACHINE & FOUNDRY CORPORATION, OF ROANOKE, VIRGINIA, A CORPORATION OF VIRGINIA

DESIGN FOR A CHAIR

Application filed September 2, 1931. Serial No. 41,002. Term of patent 14 years.

To all whom it may concern:

Be it known that we, LEWIS F. MOORE and PRESTON CRAIGHILL, citizens of the United States, residing, respectively, at Roanoke, County of Roanoke, State of Virginia, and Lynchburg, County of Campbell, State of Virginia, have invented a new, original, and ornamental Design for a Chair, of which the following is a specification, reference being had to the accompanying drawing, forming a part thereof.

The drawing is a perspective view of the chair, showing our new design.

We claim:

The ornamental design for a chair, substantially as shown.

LEWIS F. MOORE.
PRESTON CRAIGHILL.
